ILLUMINABLE OUTDOOR ADVERTISING DISPLAY STRUCTURE

Robert L. Donovan and Gerald R. Schmidt, Peoria, Ill.,
assignors to Leo Donovan Company, Peoria, Ill., a cor-
poration of Illinois

Filed Sept. 24, 1965, Ser. No. 87,155

Term of patent 14 years

(Cl. D80—1)

FIG. 1.

FIG. 2.

FIG. 3.

FIG. 4.

FIG. 5.

FIG. 1 is a perspective of an illuminable outdoor advertising display structure embodying our new design; FIG. 2 is a top plan view; FIG. 3 is a front elevation; FIG. 4 is a rear elevation; and FIG. 5 is a side elevation as viewed from either side. What is claimed is:

The ornamental design for an illuminable outdoor advertising display structure, substantially as shown.
